UNITED STATES PATENT OFFICE.

JOHN C. SHAMBOW AND GEORGE H. GOLDSMITH, OF WOONSOCKET, RHODE ISLAND,
ASSIGNORS TO SHAMBOW SHUTTLE COMPANY, OF WOONSOCKET, RHODE ISLAND,
A CORPORATION OF RHODE ISLAND.

LOOM-SHUTTLE.

1,276,582.

Specification of Letters Patent. Patented Aug. 20, 1918.

Application filed December 12, 1917. Serial No. 206,719.

To all whom it may concern:

Be it known that we, JOHN C. SHAMBOW and GEORGE H. GOLDSMITH, citizens of the United States, residing at Woonsocket, in the county of Providence and State of Rhode Island, have invented a new and useful Improvement in Loom - Shuttles, of which the following is a specification.

This invention relates to certain new and useful improvements in a loom shuttle particularly adapted for heavy work purposes, such as the weaving of bagging, and it seeks to provide improved means that will efficiently retain the yarn, which has been previously stripped from the bobbin, and placed without any central support in the yarn receiving chamber of the shuttle both against displacement and against being jammed or driven forward when the shuttle enters the box.

Further, the invention aims to provide a novel and efficient tensioning device for the feeding yarn which will readily permit the passage of irregularities in the yarn, such as knots and bunches.

The invention further resides in the features of construction and the arrangements and combinations of parts as will be herein-after described in detail and claimed in a succinct manner, reference being had to the accompanying drawing wherein—

Figure 1 is a fragmentary top plan view of a shuttle embodying the present invention, and

Fig. 2 is a side elevation thereof broken away to elucidate the construction of the yarn tensioning device.

Referring more in detail to the drawing, the numeral 1 indicates the shuttle body 40 double-pointed, as usual, and formed with the yarn receiving cavity or chamber 2 which has its side walls serrated or provided with a series of saw toothed steps or grooves 3 for interlocking engagement with the cop or cone of yarn 4. In shuttles of this nature, that is, shuttles particularly adapted for heavy work, the yarn is stripped from the bobbin and placed in the shuttle chamber without any central support. The natural action of this cone of yarn, therefore, would be to expand into at least one of the grooves of the saw tooth formation and by such interlocking relation hold the yarn in

place against being driven or jammed forwardly when the shuttle enters the box. 55

To prevent the yarn from lifting out of the chamber, a strip of fabric 5 is secured at one of said chambers beneath a clamp plate 6 by fasteners 7, the opposite end of the strip carrying a yoke 8 of truncated design 60 which is adapted to detachably engage over a pair of pins or hooks 9. Consequently the fabric 5 which extends from one end of the shuttle chamber to the opposite end, will bear on top of the yarn and hold it in position.

A tensioning device is arranged in the cavity in advance of the hooks 9 and comprises a revolute ring 10 which is held in contact with a leaf spring 11 by means of 70 its journal bearing on the eccentric 12, the latter having a head countersunk in the ring for retaining the latter thereon. A headed screw bolt or pin 13 is eccentrically passed through the eccentric and into a base plate 14 75 which also carries the spring 11 and the hooks 9, the head of said screw bolt being countersunk in the eccentric, as depicted in Fig. 2. The head of said eccentric is formed with a groove or seat 15 by which a screw 80 driver or other suitable tool may be applied for adjusting the eccentric and thereby vary the degree of tension or pressure exerted by the spring. One end of this spring is fixed as at 16 so that the leaf extends tangentially 85 to the rotatable ring.

In practice, the yarn having been placed in the shuttle, is led between the pins through the tensioning device and out through the side opening 17 formed in the shuttle. Owing to the irregularities in the yarn, it is essential that the tension be capable of giving to permit the passage of such irregularities as knots and bunches. In this instance, the ring 10 would revolve 95 about the eccentric and thereby permit free passage of the yarn while at the same time maintaining a tension by reason of the spring.

Obviously, the insertion or refilling of the 100 shuttle is facilitated since the free end of the fabric strip may readily be unhooked or disengaged in an expeditious manner to provide ready access to the chamber.

Furthermore, it will be noticed that the 105 spring 11 inclines in the direction of travel

2
of the yarn and by adjusting the eccentric the degree of tension may be adjusted to a nicety.

Having thus described our invention, 5 what we claim and desire to secure by Letters Patent is—

1. In a shuttle, a body having a chamber, and a tensioning device for the yarn as it leaves the chamber, including a revoluble 10 eccentric adjustable guide and a spring plate bearing thereagainst.

2. In a shuttle, a body having a chamber, and a tensioning device for the yarn as it leaves the chamber, including a revoluble 15 ring, an eccentric support therefor, and spring means for pressing against the ring.

3. In a shuttle, a body having a chamber, and a tensioning device for the yarn as it leaves the chamber, including a base plate, 20 an eccentric rotatably adjustable on the plate, a ring revolubly carried by the ec-

centric, and a leaf tension spring secured at one end to the plate and extending substantially tangential to the ring.

4. In a shuttle, a body having a chamber, 25 and a tensioning device for the yarn as it leaves the chamber, including a base plate, an eccentric rotatably adjustable on the plate, a ring revolubly carried by the eccentric, and a leaf tension spring secured at 30 one end to the plate and extending substantially tangential to the ring, the upper end of the eccentric having means by which it may be turned for adjustment.

In testimony whereof we have signed our 35 names to this specification in the presence of two subscribing witnesses.

JOHN C. SHAMBOW.

GEORGE H. GOLDSMITH.
